DESIGN FOR AN ADVERTISING SIGN OR THE LIKE

Ramsay G. Regester, Philadelphia, Pa., assignor to Gilco Signs, Inc., Philadelphia, Pa., a corporation of Pennsylvania

Application May 1, 1941, Serial No. 100,725

Term of patent 3½ years

To all whom it may concern:

Be it known that I, Ramsay G. Regester, a citizen of the United States of America and a resident of Philadelphia, in the county of Philadelphia and Commonwealth of Pennsylvania, have invented a new, original, and ornamental Design for an Advertising Sign or the like, of which the following is a specification, reference being had to the accompanying drawing, forming a part thereof.

In the drawing:

I claim:

The ornamental design for an advertising sign or the like, as shown.

RAMSAY G. REGESTER.
